CENTRIFUGAL REGULATOR FOR AUTOMATICALLY CONTROLLING THE ACTION MOMENT OF APPARATUS OF VARIABLE ROTATING SPEED

Josef Hövel, Köln-Brück, Germany, assignor to Klockner-Humboldt-Deutz A. G., Köln a. Rhein, Germany, a firm

Application December 20, 1950, Serial No. 201,724
In Germany December 27, 1949

8 Claims. (Cl. 64—25)

1

The invention relates to centrifugal regulators for automatically controlling the action moment of apparatus of greatly variable rotating speeds, such as fuel injection pumps or ignition apparatus of internal combustion engines. More particularly, the invention relates to regulators which have a centrifugal fly weight with slanting lateral faces engaged by corresponding slanted faces of two members mounted on the proximate ends of coaxially aligned shafts, the members and shafts being angularly shifted relative to each other by the centrifugal deflection of the fly weight.

It is an object of the invention to devise a regulating apparatus of the above mentioned kind which has an especially simple construction and for that reason also a highly reliable performance.

According to the invention, the fly weight in regulators of the kind mentioned surrounds one of the two aligned shafts and is loaded at the shaft side opposite to the weight gravity center by one or more springs which act on the weight in opposition to the centrifugal force.

The foregoing and more specific objects and features of the invention will be apparent from the embodiment exemplified on the drawing and described in the following. In the drawing, Fig. 1 is a radial cross section through the regulating apparatus, the section plane being indicated in Fig. 2 at I—I; and Fig. 2 is an axial cross section along the plane denoted in Fig. 1 by II—II.

The illustrated apparatus serves for automatically adjusting or regulating the ignition moment in a fuel injection system of an internal combustion engine operating at a greatly variable speed of rotation. The apparatus, when applied, is inserted into the drive transmission of a fuel injection pump equipped with a rotary speed regulator. The cam shaft 1 of the fuel injection pump, being also the shaft of the speed regulator, is driven from the crank shaft of the engine through a shaft 2. Shafts 1 and 2 are coaxially aligned and have their adjacent ends 3 and 4 closely spaced from each other. The illustrated regulating apparatus operates also as a clutch between the driving shaft 2 and the driven shaft 1.

The apparatus has a fly weight 5 whose major portion is located at one side of the shaft axis so that the center of gravity is spaced from the shaft axis. Weight 5 has two faces α slanted toward each other, these two faces are engaged by respective counter faces of two members 6 and 7 mounted on shafts 2 and 1 respectively. Members 6 and 7, together with the appertaining shafts, are twisted relative to each other when the fly weight is centrifugally deflected due to large vari-

2

ations in the rotary speed of the engine. As a result, the fuel injection pump is caused to operate at an earlier or later moment dependent upon the rotary speed of the engine. The slide faces α of the fly weight 5 form together an acute angle denoted by α . The proportions are such that the fly weight 5 is not displaced by the torque which it transmits but can yield only to the centrifugal and spring forces acting on the weight. To this end, as shown, the weight faces α lie in planes substantially radial to the shaft axis so that the transmitted torque does not produce a radial force component.

The two members 6 and 7 are essentially designed as discs and have respective hubs 8 and 9 firmly secured on the ends of respective shafts 2 and 1. The disc portion of member 7 serves also as a holder for the speed regulator fly weights 10 which cooperate with an axially displaceable regulator sleeve 11 on shaft 1 in the manner known for speed regulators and not essential to the invention proper. The two disc portions of members 6 and 7 are axially spaced from each other to provide an annular interstice for accommodating the fly weight 5. The fly weight 5 has a shape adapted to that of the annular interstice and, hence, has also a disc-like design. The weight 5 is guided for radial deflection between the disc surfaces of members 6 and 7. The fly weight 5 has the particularity that it surrounds one of the shafts and is subjected to spring loading on the side of the shaft opposite to the location of the main mass, i. e. opposite to the center of gravity of the weight. The spring loading is effected by means of a helical compression spring 12, although it will be understood that several springs or spring means of a different design may instead be provided.

The spring 12 is located in a recess 13 of the fly weight. The recess 13 is open at both axial sides, and the spring is secured against lateral dislocation by the adjacent disc surfaces of members 6 and 7. In the illustrated embodiment, the hub 8 of member 6 has sleeve shaped projection 14 which forms an extension of the shaft 2 and is centered upon the hub 9 of the disc member 7. The fly weight 5 surrounds the projection 14 with an elongated opening 19 which permits a radial displacement of weight 5 from the illustrated position only in the direction of the centrifugal force. The spring 12 abuts against the projection 14 through an adapter piece 20.

Weight 5 has two recesses 15, each having parallel walls of which one forms the above mentioned slide face α . The two members 6 and 7

have respective slide blocks 16 which engage the recesses 15 respectively and form the counter faces that slide on the weight faces *a*. The slide blocks 16 are revolvable on pins. Each pin is composed of a bushing 17 and a screw 18. One screw is secured to the disc portion of member 6 and the other to the disc portion of member 7. In Fig. 2 one of the slide blocks 16 with the appertaining screw 18 is shown in an angularly displaced position by dot-and-dash lines.

While reference was made in the foregoing to the application of the illustrated regulator for controlling the injection moment of the fuel injection pump, the same apparatus lends itself readily for automatically controlling the action moment of ignition apparatus for internal combustion engines and is also advantageous for all other purposes where it is essential to twist two mechanically coupled shafts relative to each other during their power transmitting performance so that apparatus driven through these coupled shafts are operated at an earlier or later moment depending upon the speed of rotation.

It will be recognized that apparatuses according to the invention have an extremely simple design. For that reason such apparatus secure a performance of highest reliability.

I claim:

1. Centrifugal device for controlling the action moment of apparatus of variable rotary speed such as fuel injection pumps and ignition apparatus of internal combustion engines, comprising two coaxial aligned shafts having proximate respective ends, a fly weight surrounding one of said shafts and having a gravity center eccentric to the shaft axis, said weight having two lateral faces slanted toward each other, two members rigidly joined with said respective shafts and having respective counter faces engaging said two weight faces respectively for angularly shifting said shafts relative to each other due to centrifugal deflection of said weight, and spring means disposed between said weight and said one shaft at the shaft side opposite said gravity center and having relative to said weight a loading force opposed to the centrifugal force.

2. Centrifugal device for controlling the action moment of apparatus of variable rotary speed such as fuel injection pumps and ignition apparatus of internal combustion engines, comprising two coaxial aligned shafts having proximate respective ends, a fly weight surrounding one of said shafts and having a gravity center eccentric to the shaft axis, said weight having two faces extending substantially in respective planes radial to the shaft axis and intersecting each other at an acute angle, two members rigidly joined with said respective shafts and having respective counter faces engaging said two weight faces respectively for angularly shifting said shafts relative to each other due to centrifugal deflection of said weight, and compression spring means

disposed between said one shaft and said weight at the shaft side opposite said gravity center for loading said weight in opposition to centrifugal force.

3. Centrifugal device for controlling the action moment of apparatus of variable rotary speed such as fuel injection pumps and ignition apparatus of internal combustion engines, comprising two coaxial aligned shafts having proximate respective ends, a fly weight surrounding one of said shafts and having a gravity center eccentric to the shaft axis, said weight having two angularly displaced recesses each having two parallel wall faces mutually spaced in the peripheral direction of the weight, two coupling members rigidly joined with said respective shaft ends and having two revolvably pivoted slide blocks respectively in slidable engagement with said respective recesses for relatively twisting said shafts due to centrifugal deflection of said weight, and spring means disposed between said weight and said one shaft at the shaft side opposite said gravity center and having relative to said weight a loading force opposed to the centrifugal force.

4. In a device according to claim 3, said two coupling members having mutually parallel disc faces axially spaced from each other, and said weight having a flat shape and being disposed between said two disc faces and guidingly engaged by said disc faces.

5. In a device according to claim 4, said weight having an opening eccentrically located at said shaft side and open toward both axial sides of said weight, and said spring means being disposed in said opening and confined therein by said two disc faces.

6. In a device according to claim 5, said weight having an oblong center bore traversed by said one shaft, said bore having its longitudinal extent in the direction of the centrifugal weight force and having a width corresponding to the outer diameter of said one shaft where it traverses the bore so as to permit only a radial deflection of said weight in the centrifugal force direction.

7. In a device according to claim 6, said spring means consisting essentially of a helical compression spring and a spring seat member, said seat member having an arcuate surface adapted to the periphery of said one shaft and engaging said periphery, and said spring abutting against said seat member and against a radially opposite wall portion of said weight opening.

8. In a device according to claim 3, said two recesses being located at an acute angle to each other and having their respective inner wall faces extend in substantially radial planes relative to the shaft axis whereby said weight is capable of transmitting torque between said shafts without radial deflection of said weight.
